(57) **CLAIM**

The ornamental design for a cooler, as shown and described.

DESCRIPTION

FIG. 1 is a front top left perspective view of the cooler of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front bottom right environmental view thereof illustrating the cooler in cooperation with a cooler stand; and,

FIG. 9 is a front top left environmental view illustrating the cooler in cooperation with a cooler stand.

The portions of the cooler illustrated in broken lines form no part of the design claim for the cooler.
